UNITED STATES PATENT OFFICE.

ARTHUR MEYER, OF BERLIN, GERMANY.

TRICK WRITING IMPLEMENT.

1,153,809.

Specification of Letters Patent. Patented Sept. 14, 1915.

Application filed May 28, 1914, Serial No. 841,672. Renewed June 23, 1915. Serial No. 35,942.

To all whom it may concern:

Be it known that I, ARTHUR MEYER, merchant, a subject of the King of Prussia, and residing at Stallschreiberstrasse No. 58, Berlin, S. 14, Germany, have invented certain new and useful Improvements in Trick Writing Implements, of which the following is a specification.

The present design consists in a trick writing-implement serving as a device for a practical joke, which is constructed in such a manner that when used for writing it falls apart owing to the action of a spring, and in this way creates a surprise.

An example of construction of the design as a writing pencil is illustrated in the accompanying drawings.

Figure 1 shows the pencil in the assembled condition ready for using. Fig. 2 a longitudinal section through the same, in which the position of the parts immediately after falling apart is indicated in dotted lines. Fig. 3 a cross section through the pencil.

As shown in the drawings, the stem or barrel of the writing pencil consists of two longitudinal halves *a* and *b*, between which a spring *c* is inserted which tends to force the two halves apart. The two parts *a* and *b* of the stem are held together by caps, casings or the like engaging over the ends. The one cap *d* can at the same time be fixed to one half *b* of the stem, for example, a plate may be soldered on. The other casing or cap is formed by the point portion *e*, which at the same time carries the lead, pen-nib or the like. This point portion *e* is with its cap *f* pushed loosely over the two halves so that it is held upon these by the pressure of the spring *c*, which tends to move the two halves of the stem apart.

Now, if such a writing implement is taken in the hand in order to write, upon this attempt to use the same the point portion *e* is lifted sidewise releasing the ends of the two halves *a* and *b* of the stem which are forced apart by the spring *c*, as is indicated in dotted lines in Fig. 2.

Instead of the point *e* for blacklead pencil, as illustrated, the front part of a writing pen can also be employed. Also a removable cap or casing can be placed upon this in order to protect the lead, as has been usual many times before, and the two halves of the stem may be held together by this means. In this case the springing apart of

the halves of the stem will take place when the protecting cap is withdrawn.

As is shown in the drawings, the present example of construction is formed of sheet metal; it can, however, be made in practice 60 also in any other desired suitable material. Similarly the same can be assembled from a plurality of longitudinal parts instead of from two which are forced apart by a spring.

The spring *c* can be so arranged that it is 65 connected with the two parts *a* and *b* of the stem in any suitable manner to form a hinge so that when the two parts are forced apart they are still connected by means of the spring.

As shown in the drawing the spring may consist of two legs lying alongside each other and a coil or bend connecting them, the foot of one leg being bent around a cross bar fixed in the one member *a*, and the 75 coil or bend encircling a cross bar or pin fixed in the other member *b*, the free leg of the spring bearing against the inner face of the member *b*.

Having now particularly described and 80 ascertained the nature of my said invention and in what manner the same is to be performed, I declare that what I claim is:—

1. A trick writing implement with a stem 85 consisting of separated members, removable caps pushed on at either end and a spring under tension arranged in the interior of the stem, forcing asunder the different members when released.

2. A trick writing implement with a stem 90 consisting of several longitudinal members, two caps keeping together the said members against the tension of a spring, one cap being attached to one of the longitudinal members, the other one being connected to a lead 95 holder.

3. A trick writing implement with a stem 100 consisting of several longitudinal members, two caps keeping together the said members against the tension of a spring, one cap being attached to one of the longitudinal members, the other one being shaped as a nib holder.

4. A trick writing implement with a stem 105 consisting of several longitudinal members, two caps keeping together the said members against the tension of a spring, one cap being attached to one of the longitudinal members, the other one being shaped as protecting cap.

5. A trick writing implement with a stem consisting of several longitudinal members, two caps keeping together the said members against the tension of a spring; the spring being connected to the members of the stem.
6. A trick writing implement comprising a stem consisting of a plurality of separated members, end caps confining the same and resilient means between the members of the stem adapted to force said members apart upon removal of an end cap.
7. A trick writing implement comprising a stem consisting of a plurality of longitudinal members, resilient means adapted to normally force said members apart, a cap at each end inclosing the ends of the longitudinal members and holding them together against the force of the resilient means.
8. A trick writing implement comprising a stem consisting of a plurality of longitudinal members, resilient separating means between said members and connected to each member, and caps confining the ends of said longitudinal members against the force of the resilient means.
9. A trick writing implement comprising a stem consisting of a plurality of separated longitudinal members removable caps confining the ends of said members and a spring under tension located between the said longitudinal members.
10. A trick writing implement comprising a stem consisting of a plurality of longitudinal members, a spring under tension engaging the inner faces of the same and tending to force them apart, a cap at each end of said stem, one cap attached to one longitudinal member and the other cap removably engaging the opposite ends of the stem members and carrying a marking instrument.
11. A trick writing implement comprising a stem consisting of a plurality of longitudinal members, a bent spring located between the said members and tending to normally force them apart, and caps confining the ends of said members against the force of the spring, one of said caps adapted to be forced from the ends of the members by side pressure thereon.
12. A trick writing implement comprising a stem consisting of semi-tubular members, a cap rigidly attached to one semi-tubular member and inclosing the end of the other semi-tubular member, another cap removably engaging the opposite ends of the semi-tubular members and carrying a marking instrument; and a spring under tension rigidly secured within one semi-tubular member and having a hinge connection with the opposing semi-tubular member.
13. A trick writing implement comprising a stem consisting of a pair of longitudinal members, removable caps inclosing either end of the stem and a spring member under tension within the stem tending to force the stem members apart upon the removal of an end cap.

In testimony whereof I affix my signature in presence of two witnesses.

ARTHUR MEYER.
